Eric Wedemeyer, Floral Park, N. Y., assignor to Hamilton Art Metal Corporation, New York,
N. Y., a corporation of New York

Application December 23, 1949, Serial No. 6,805

Term of patent 7 years

(Cl. D85—2)

To all whom it may concern:

Be it known that I, Eric Wedemeyer, a citizen of the United States of America, residing at Floral Park, county of Nassau, State of New York, have invented a new, original, and ornamental Design for a Combined Ash Tray and Snuffer, of which the following is a specification, reference being had to the accompanying drawing, forming part thereof.

Fig. 1 is a side view of a combined ash tray and snuffer, showing my new design, the other side being like the side shown;

Fig. 2 is a top plan view thereof.

I claim:

The ornamental design for a combined ash tray and snuffer, substantially as shown and described.

ERIC WEDEMEYER.
